UNITED STATES PATENT OFFICE.

BENJAMIN F. SEYMOUR, JR., OF DENVER, COLORADO.

AEROPLANE FLYING-MACHINE.

1,070,849.

Specification of Letters Patent. Patented Aug. 19, 1913.

Application filed December 3, 1909; Serial No. 531,187. Renewed January 17, 1912. Serial No. 671,652.

To all whom it may concern:

Be it known that I, BENJAMIN F. SEYMOUR, Jr., a citizen of the United States, residing in the city and county of Denver 5 and State of Colorado, have invented certain new and useful Improvements in Aeroplane Flying-Machines; and I do declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

My invention relates to improvements in aerial apparatus or flying machines of the aeroplane type.

In my present improvement I employ 20 propellers of the helicopter type but so constructed that they resist the outward tendency of the air due to centrifugal force, the object of such construction being to prevent the formation of an atmospheric cavity or 25 vacuum due to the rotary action of the propeller at the necessary speed. By virtue of my improved construction the tendency to produce such a cavity or vacuum is overcome and there is practically no limit to the 30 speed at which the propellers may be rotated; while with helicopters of the ordinary type, their efficient rotary action is limited, since there is always a tendency to the production of an atmospheric cavity or vacuum, 35 whereby the atmospheric resisting medium is either absent or so rarefied as to be of little value.

In my improved construction I provide the propellers with inner and outer casings 40 or housings, through which the blades pass. The outer casings or housings are also equipped with atmospheric scoops or buckets, adapted to catch the atmosphere and direct it inwardly through the outer housing 45 of the propeller, thus aiding in maintaining a proper atmospheric resisting medium for the efficient action of the propellers under all circumstances, regardless of the speed to which they are driven. I employ propellers 50 of this construction both for lifting purposes and for horizontal propulsion. The lifting propellers rotate on vertical axes, while the horizontal-propulsion propellers rotate on horizontal axes when the flying 55 machine or airship is in a horizontal posi-

tion. In any event, the axes of the lifting propellers are at right angles to those of the horizontal-propulsion propellers.

Having briefly outlined my improved construction, I will proceed to describe the same 60 in detail, reference being made to the accompanying drawing in which is illustrated an embodiment thereof.

In this drawing: Figure 1 is a section taken through an airship or flying machine 65 equipped with my improvements. Fig. 2 is a top plan view of one of the propellers. Fig. 3 is a similar view showing a slightly modified form of construction. Fig. 4 is a top plan view of the airship which, as 70 illustrated in the drawing, is of the monoplane type.

The same reference characters indicate the same parts in all the views.

Let the numeral 5 designate a platform 75 upon which are mounted posts 6, connected by means of braces 7 with an upper framework 8, forming a support for an aeroplane 9, the latter being connected with the framework 8 by means of supports 10. The 80 aeroplane is provided with openings in which cylindrical casings 12 are located, the latter being open at both extremities and adapted to cooperate with propellers 13 which are mounted on shafts 14, the axes of 85 the propellers being coincident with those of the casings 12. Connected with the supports 10, above the aeroplane and extending over the propellers in cruciform style is a skeleton frame 14, through whose central 90 portion the upper extremity of the propeller shaft passes. This skeleton structure forms a bearing for the upper extremity of the shaft. Each propeller, which is of the helicopter type, is composed of blades 15 which 95 pass through inner and outer housings 16 and 17 respectively. As shown in Fig. 1, the outer housing is cylindrical while the inner housing is frusto-conical, its inner walls being outwardly flared from their lower edge, thus having a tendency to cause the air passing through the propeller to move toward the center to neutralize the outward tendency due to centrifugal force. 100 These housings trap the air so to speak and maintain an atmospheric medium of sufficient density for efficient use, regardless of the speed at which the propellers are operated. In order to further supply the propellers with an atmospheric resisting me- 105

dium of the required density, I equip the outer housing with atmospheric scoops or buckets 18, which project outwardly from the outer housing and are arranged to catch the atmosphere outside of the body of the propeller and direct it inwardly through openings 19 in the said housing, as indicated by the arrows in Figs. 2 and 3.

As shown in Fig. 1, the lifting propellers 10 and the horizontal propellers are of precisely the same construction, the latter, however, being mounted upon a horizontal shaft 20, journaled in bearings 21, made fast underneath the platform 5.

15 In the form of construction shown in Fig. 3, both housings 16 and 17 are cylindrical and two sets of blades are employed, one set, designated 22, being interposed between the inner and outer housing and secured thereto by means of bolts 23 and 24; while the other set 27 are secured at their inner extremities to a hub 25 through which the shaft passes, their outer extremities being connected with the inner housing by bolts 26, the inner blades 27 having their outer extremities interposed between the inner extremities of the blades 22. In this form of construction the inner housing, as well as the outer housing, is equipped with the atmospheric scoops 18, the inner housing being also provided with openings 28, through which the air is directed inwardly against the blades 27.

As shown in the drawing (see Fig. 1), 35 the apparatus is equipped with an engine 30, having a shaft 31 connected with the horizontal propeller shaft 20 by meshing gears 34 and 35; while the vertical propeller shafts 14 are connected with the engine 40 shaft by means of gears 32 and 33, shafts 36 and bevel gears 37 and 38. The gears 37 are slidably mounted on their respective shafts and are provided with collars 39 engaged by levers 40 fulcrumed at 41 and connected, as shown at 42, with operating rods 43. By operating these levers the gears 37 may be thrown into or out of mesh with their companion gears 32 and 33, as will be readily understood.

50 Below each propeller 13 and mounted on the post 6 of the frame work, is a cone-shaped deflector 44, having a hub 45 through which the shaft 14 passes. These deflectors are equipped with slots 46 through which the posts 6 pass and they are adjustable on the latter by means of set bolts 47.

When the apparatus is in use both the horizontal-propulsion propellers and the lifting propellers may all be in motion and in 60 this event the machine will rise in the atmosphere in a direction inclined to the horizontal, the angle of movement depending upon the relation between the lifting and horizontal-propulsion forces. Either of 65 these forces may be regulated as may be de-

sired or wholly discontinued at the will of the operator and as circumstances and conditions may dictate.

Attention is called to the fact that where the machine is equipped with a number of lifting propellers, the individual propellers may be rotated in reverse directions. For instance, referring to Fig. 4, the two propellers at the extreme right and left, as well as those at the top and bottom of the sheet, should be rotated in reverse directions in order to overcome the tendency of the entire machine to rotate, as might result from the constant rotation of the entire set of propellers in one direction.

Having thus described my invention, what I claim is:

1. A propeller provided with blades and housings equipped with scoops, the housings having openings adjacent the scoops, substantially as described.

2. A propeller provided with blades and equipped with a housing surrounding the blade zone and having atmospheric scoops in communication with the blade zone inclosed by the housing, substantially as described.

3. A propeller provided with blades and having a housing at the outer extremity of the blades, the said housing having exteriorly projecting atmospheric scoops communicating with the space inclosed by the housing, substantially as described.

4. A propeller provided with blades, and having a housing at the outer extremity of the blades, the housing having exteriorly projecting atmospheric scoops, the housing having openings adjacent the scoops to allow the air to pass inwardly, for the purpose set forth.

5. A propeller equipped with blades and provided with a housing located intermediate the blade zone, and equipped with atmospheric scoops, the housing having openings adjacent the scoops, for the purpose set forth.

6. A propeller equipped with blades and provided with a housing located intermediate the blade zone, and equipped with atmospheric scoops, the housing having openings adjacent the scoops, arranged to deliver air into the space inclosed by the housing, substantially as described.

7. An air ship propeller equipped with blades and having a housing provided with atmospheric scoops protruding beyond the housing, the latter having openings adjacent the scoops, for the purpose set forth.

8. A propeller provided with blades and having housings equipped with scoops, said housings having openings adjacent the scoops, for the purpose set forth.

9. A propeller provided with blades, and having an outer housing equipped with atmospheric scoops in communication with the

housing for delivering air to the blades of the propeller, for the purpose set forth.

10. A propeller provided with blades and having inner and outer housings, the inner housing being equipped with atmospheric scoops and provided with openings adjacent the scoops to allow the air to pass inwardly, for the purpose set forth.

11. A propeller comprising housings equipped with atmospheric scoops, the said housings having openings adjacent the scoops, and inner and outer sets of series of blades arranged in staggered relation, for the purpose set forth.

15. 12. A propeller provided with blades and having inner and outer housings, each housing being equipped with atmospheric scoops, having openings adjacent the scoops, for the purpose set forth.

20. 13. An air ship propeller provided with blades and having an inner and an outer housing, one housing being at the outer extremity of the blade zone, and the other housing being intermediate the blade zone, the two housings being provided with atmospheric scoops and provided with openings adjacent the scoops, for the purpose set forth.

30. 14. A propeller having a plurality of concentric housings, a set of blades located within the innermost housing, and another set of blades interposed between the housing, the housings being equipped with scoops in communication with the interior of the housings for the purpose set forth.

35. 15. A propeller having inner and outer housings, and blades arranged within the

40. housings, the inner housing being flared outwardly from its rearward edge, substantially as described.

16. An air ship propeller having an inner and an outer housing, the inner housing being outwardly flared from its rearward edge and located intermediate the blade zone, substantially as described.

17. A propeller provided with blades having a housing equipped with deflectors, the housing having openings adjacent the deflectors through which fluid is directed by the deflectors into the interior of the housing, substantially as described.

18. A propeller provided with blades equipped with a housing, and having a deflector, the housing having an opening arranged adjacent the deflector through which opening the fluid is delivered by the deflector into the blade zone inclosed by the housing, substantially as described.

19. In combination, a propeller having blades, housings mounted upon said blades, and means arranged in fixed relation to said blades for directing motive fluid against the blades between said housings.

20. In combination, a propeller having blades, housings mounted upon said blades, and means arranged in fixed relation to said blades for directing motive fluid against the blades.

In testimony whereof I affix my signature in presence of two witnesses.
